DESIGN FOR A BOTTLE

Garland D. Runnels, New York, N. Y.

Application November 8, 1945, Serial No. 123,578

Term of patent 14 years

(Cl. D58—8)

To all whom it may concern:

Be it known that I, Garland D. Runnels, a citizen of the United States, residing at New York, in the county and State of New York, have invented a new, original, and ornamental Design for Bottles, of which the following is a specification, reference being had to the accompanying drawing, forming part thereof.

Fig. 1 is a front view of a bottle, showing my new design,

Fig. 2 is a side elevation thereof, and

Fig. 3 is a plan view thereof.

I claim:

The ornamental design for a bottle, as shown.

GARLAND D. RUNNELS.
